FRED G. MEYER, OF DETROIT, MICHIGAN

BOTTLE-CAPPING MACHINE.

1,425,672.

Specification of Letters Patent. Patented Aug. 15, 1922.

Application filed September 25, 1919. Serial No. 326,203.

To all whom it may concern:

Be it known that I, FRED G. MEYER, a citizen of the United States, residing at Detroit, in the county of Wayne and State 5 of Michigan, have invented a new and useful Bottle-Capping Machine, of which the following is a specification.

This invention relates to bottle capping machines and more particularly to a hand 10 power plunger press for bottle capping machines, which may be considered as an improvement upon the construction disclosed in application Serial No. 299,921.

It is the object of the invention to improve 15 a bottle capping machine of the type comprising a reciprocatory plunger carrying a cap-engaging head, and means for manually actuating said plunger by providing such a machine with a very simple and inexpensive frame and head adjustable upon 20 said frame for mounting said plunger.

This object is attained by the structural arrangement hereinafter described and illustrated in the accompanying drawings, 25 wherein,

Fig. 1 is a side elevation of the machine, the cap-engaging head of the plunger being shown in section.

Fig. 2 is a front view of the same. 30 Fig. 3 is a fragmentary rear view of an intermediate portion of the frame, showing the parts mounted thereupon.

In these views the reference character 1 designates a frame, which may be formed 35 of a single length of strap iron, a center portion of which is engaged beneath a base 2 and secured thereto by screws 3, corresponding portions of the strap-iron being extended convergently upward from 40 said base for approximately one half the height of the frame and then being extended vertically in a slightly spaced relation maintained by spacer blocks 4, which are secured to the strap iron by rivets 5 or other suitable fastenings. The base 2 is preferably formed of wood, and is engaged by the frame 1 near one of its ends 45 so as to leave ample room upon said base for the bottle 6 or other receptacle to be 50 capped. Upon the upper portion of said frame there is adjustably mounted a head 7, which provides a slide bearing for the vertically reciprocatory plunger 8 carrying beneath said head the cap-engaging 55 head 9, having in its under face the recess 10 for receiving a cap 11. The head

7 has a tongue 12 projecting rearwardly therefrom and engaging snugly between the spaced vertical portions of the frame, this engagement being maintained by a bolt 60 13 and winged-nut 14. A flange 15 is formed at the rear edge of said tongue to bear against the corresponding edge of the frame and thus counteract any tendency of the head 7 to swing about the bolt 13. 65 The upper end of the head 7 is slotted at 16 in registration with the space between the vertical portions of the strap-iron 1, and the plunger 8 extends at its upper end into the slot 16 and is engageable within 70 said slot by a lever 17 extending between said vertical portions of the strap-iron 1 and pivoted upon a bolt 18 mounted in said portions. Thus the lever 17 constitutes a means for exerting a considerable 75 pressure upon the plunger 8 to shift the same downwardly with sufficient force to deflect the skirt portion of a cap, such as is shown at 11, to permanently engage said cap with the mouth of a bottle. Return of the plunger 8 to its normal raised 80 position is effected by a coiled spring 19 extending between a pair of lugs 20 respectively integrally formed upon the head 9 and the upper portion of the head 7. 85 The action of said spring upon the plunger is limited by the engagement of the head 9 with the bottom of the head 7. As disclosed by the drawing, the head 7 is adapted to occupy two different positions 90 of adjustment upon the frame 1, one of said positions being that occupied by the head in said drawing and the other a somewhat higher position in which the bolt 18 forming a pivot for the lever is engaged 95 in the hole 21 of the frame, and the bolt 13 which holds the head 7 in place is engaged in the hole which, as now shown, receives the bolt 18.

The described construction permits the 100 use of relatively inexpensive materials and yet secures a strength fully adequate to insure durability and rigidity. The adjacent relation of the vertical portions of the strap-iron 1 conveniently provides a 105 space within which the head 7 and lever 17 may be mounted, and the divergent lower portions of said strap-iron establish a central location of the vertical portions with respect to the sides of the base and 110 exercise a brace effect to resist lateral bending of the frame and provide an expedi-

tious yet secure means for assembling the frame upon the base.

The vertical adjustability of the head 7 with respect to the frame permits bottles 5 of different heights to be positioned upon the base 2 beneath the plunger 8, and the number of available positions of adjustment may be increased merely by providing additional holes 21 properly located.

10 What I claim is:

A plunger press, comprising a base, a frame formed of strap-metal having spaced upper portions and having divergent lower

portions engaging said base, a head having an extension between said upper portions, means securing said extension to the frame, a flange upon said head engaging said upper portions to prevent swinging of the head about its securing means, a plunger vertically reciprocatory in said head, 20 and a lever pivoted upon said frame between said spaced portions thereof for actuating said plunger.

In testimony whereof I sign this specification.

FRED G. MEYER.
